ELECTROMAGNETIC RELAY

Harold Akroyd, Denton, near Manchester, England, assignor to Oldham & Son Limited, Denton, near Manchester, England, a British company

Application May 26, 1945, Serial No. 595,908
In Great Britain April 21, 1944

5 Claims. (Cl. 200—87)

1

This invention relates to electromagnetic relays of the type in which an electric contact is closed when the relay is not energised and is opened when the relay is energised.

Relays of this type, for certain purposes, are required to operate both to close and to open the contact for a variation in the current through the relay which is a fraction of the normal current. For instance a relay in a circuit in which, say, 50 volts are normally on the relay, may be required to close its contact if the volts drop to 30, and to open its contact if they rise to 40.

The adjustment needed to cause a relay to fulfil such conditions usually consists in varying the tension of the spring operating to pull the armature away from the pole-piece.

The object of the invention is a relay which can be adjusted to operate with a predetermined variation of current without varying the spring tension. A further object is a relay of simple construction provided with the required means of adjusting its operating limits.

According to the invention, a relay of the type described, having a "fixed" contact and a contact moving with the armature, is provided with means for adjusting the air-gap of the armature when the armature is in attracted position and independent means for adjusting the air-gap when the contacts are closed.

Conveniently, the electromagnetic relay according to the invention comprises a moving contact which is adjustable in position relatively to the armature. The moving contact may be mounted on a flexible member connected with the armature at one end, and adjusting means may be provided for bending the flexible member to or from the armature.

In one practical form of the invention the electromagnetic relay comprises an adjusting screw traversing the armature or piece attached thereto and adapted to abut against the pole-piece attached thereto, and a nut on the said screw engaging the flexible member and adapted to bend it to or from the armature.

In the accompanying drawings, which show by way of example three constructional forms of a relay according to the invention,

Figure 1 is a section of a relay and

Figures 2 and 3 are part sections of alternative forms of relay.

In the drawings like reference numerals designate similar parts.

Referring to Figure 1, the magnet core 1 is provided with a winding 2 and iron end pieces 3 and 4, the latter forming a pole-piece at 5. An

2

armature 6 is pivoted at 7 to the end piece 3 and is drawn away from the pole-piece 5 by the spring 8. A flexible member 9 carrying the moving contact 10 is attached to the armature 6 at 11. The relay is carried on a base-plate (not shown) by brackets 12, and a bracket 13 carries the "fixed" contact 14. A screw 15 passes through the armature 6 so that its end abuts on the pole-piece 5. The screw 15 passes through a slot in the end of the flexible member 9, and a nut 16 on the screw 15 bears on it.

The relay is shown in energised position, with its contacts 10 and 14 open. By moving the screw 15 more or less through the armature 6, the width of the air-gap at 5 may be adjusted and, thereby the relay may be adjusted to operate to close its contacts 10, 14 for a predetermined value of the current through its winding less than the normal current. When this adjustment has been effected, the screw 15 may be held stationary and the nut 16 turned to vary the distance of the moving contact 10 from the armature, to adjust the width of the air-gap at 5 when the relay is de-energised, and thereby the relay may be adjusted to operate to open its contacts for a predetermined value of the current, without disturbing the previously made adjustment for operation to close the contacts.

If, on the other hand, the adjustment of the air-gap when the contacts are closed is correct, and it is desired to alter the adjustment of the air-gap when the contacts are open, this may be effected by turning together the screw 15 with its nut 16. Thereby the latter adjustment is made without affecting the former adjustment. The two adjusting means are, therefore independent, in the sense that they enable either adjustment to be made without affecting the other.

The spring 8 acts at a point close to the pivot 7, so that its tension is appreciably the same for the two positions of the armature.

Figure 2 shows an alternative form of the adjusting means, in which the screw 15 for adjusting the air-gap when the contacts are open is in a bracket 17 attached to the end piece 4 to which it forms a lateral extension, while the adjustment of the air-gap when the contacts are closed is effected by the screw 18 in a piece 19 attached to the armature and overlapping the said extension, against which piece 19 the screw 15 abuts. The fixed contact 14 is shown non-adjustable in its bracket 13, but it may be made adjustable, as in Figure 1, by means of the screw 20.

Figure 3 shows another alternative form, in which the screw 15 is disposed as in Figure 1, while the moving contact 10 is on a screw 21 in the armature 6.

In practice it is generally required that the relay shall close and open its contacts as a result of small current variation and for this the change in air-gap in the two positions of the armature is made very small. It has been exaggerated in the drawings for the sake of clearness.

I claim:

1. An electromagnetic relay comprising in combination, a pole-piece, an armature pivoted for attraction towards the pole-piece when the relay is energised, a pair of co-operating electrical contacts to be opened when the relay is energised, one of said contacts being stationary and the other movable with and adjustable relatively to the armature, a first adjusting means to maintain a permanent air gap between the armature and the pole-piece and for regulating the air gap when the armature is attracted, and a second adjusting means for independently regulating the said air gap when the contacts are closed.

2. An electromagnetic relay comprising in combination, a pole-piece, an armature pivoted for attraction towards the pole-piece when the relay is energised, a pair of cooperating electrical contacts to be opened when the relay is energised, one of said contacts being stationary and the other movable, a resilient carrier for the movable contact said carrier being mounted on the armature for movement therewith, a first adjusting means movable relatively to said carrier to maintain a permanent air gap between the armature and the pole-piece and for regulating the air gap when the armature is attracted, and a second adjustable means for independently regulating the said air gap when the contacts are closed.

3. An electro-magnetic relay as claimed in claim 2, wherein the first adjusting means comprises a screw passing through the armature to abut on the pole-piece and the second adjusting means comprises a nut on the screw to engage

said carrier, whereby adjustment of the movable contact relatively to the armature may be effected without affecting said air-gap or adjustment of the air gap may be effected without affecting the position of the movable contact relatively to the armature.

4. An electromagnetic relay as claimed in claim 2, wherein the first adjusting means comprises a first screw passing through an extension of the pole-piece to abut on an extension of the armature and the second adjusting means comprises a second screw passing through said extension of the armature and engaging said carrier, whereby adjustment of the movable contact relatively to the armature may be effected without affecting said air-gap or adjustment of the air gap may be effected without affecting the position of the movable contact relatively to the armature.

5. An electromagnetic relay as claimed in claim 2, wherein the first adjusting means comprises a first screw passing through the armature to abut on the pole-piece and the second adjusting means comprises a second screw passing through the armature and associated with the movable contact, whereby adjustment of the movable contact relatively to the armature may be effected without affecting said air-gap or adjustment of the air gap may be effected without affecting the position of the movable contact relatively to the armature.
